ARTHUR KORN, OF BERLIN-CHARLOTTENBURG, GERMANY, ASSIGNOR TO C. LORENZ
AKTIENGESELLSCHAFT, OF BERLIN-TEMPELHOF, GERMANY

PICTURE-TELEGRAPH SYSTEM

Application filed July 28, 1927, Serial No. 208,936, and in Germany August 3, 1926.

This invention relates to systems for the synchronization of picture telegraphs, telautographs and the like.

The synchronization of such devices when only one line of frequency was available for the transmission was hitherto generally effected in such a manner that synchronizing signals were sent from the transmitting to the receiving station through the same transmission line or wireless transmitting channel during the intervals in which transmission of picture or writing elements was not taking place.

When rolls or drums were used for the reception of the picture or of the writing characters at the transmitter or at the receiver, the synchronization could be effected only after one revolution, since between the beginning and the end of the lines of the picture or of the manuscript foil there was an interval which could be utilized for the transmission of the synchronization signals.

In the system of synchronization according to the present invention there are transmitted from the transmitting to the receiving stations, simultaneously with the signals to be transmitted, corresponding to the picture or writing character elements, periodic signals of a given frequency which are of a different intensity from those of the superimposed picture signs, which periodic signals are separated from the picture signs at the receiving station and utilized for regulating the synchronization.

As current limiting devices for the reception of the synchronizing currents there may be used amplifier valves or other suitable relays which exhibit saturation phenomena.

In order that the said invention may be clearly understood and readily carried into effect, the same will now be described more fully with reference to the accompanying drawings, which illustrate by way of ex-

ample two systems of carrying out the invention and in which:-

Figures 1 and 2 illustrate respectively in diagrammatic fashion a transmitting station and a receiving station for wireless transmission.

Figures 3, 4 and 5 are various diagrams of the frequencies utilized for the purpose in view.

Figure 6 shows a transmitting station for line transmission, and

Figures 7, 8 and 9 are various diagrams of the frequencies generated in the case of the arrangement shown in Figure 6.

Fig. 10 is a diagrammatic view of the receiver.

In Figure 1 there is shown a well known telautographic transmitter in which a rotatable metal cylinder 1 carries a metal foil on which the picture to be transmitted is traced in a non-conducting substance.

A metal feeler pin 2 makes or does not make contact on the foil according as it strikes a conducting or a nonconducting point of the picture. With the cylinder 1 there rotates an interrupter disc 4 on which a spring 4' periodically makes contact. The voltages from a battery 3 pass through the resistance 5, the interrupter disc 4 and through the resistance 6, which is connected in parallel to the telautographic transmitter, into the grid of a wireless transmitter or into a modulation valve of such a transmitter; the path to the latter is indicated by the plug contact 7.

As long as the feeler pin 2 does not make contact periodic synchronizing signals of the kind shown in Figure 5 will be produced. As soon however as the feeler pin 2 makes contact, the signals corresponding to the picture elements are superimposed, since the resistance 6 is now cut out, on top of the synchronizing current impulses determined by the interrupter disc 4 and its speed of rotation, for instance in the manner indicated in Fig.

ure 3, in which *s* represents the synchronizing impulses and *p* represents the picture current signals.

In the receiving apparatus shown in Figure 2, the signs which are received by means of the high frequency or intermediate frequency amplification and audion (detector) and which are again of the shape shown in Figure 3, are passed through the plug contact 8 into a thermionic valve 9 in such manner that the voltages, which are of the shape according to Figure 3, are conveyed between the grid 9' and the cathode 10, and, proportionally amplified, change the anode current 15 (supplied from the anode battery 12) which passes from the cathode 10 to the anode 11. The anode current passes through the photographic picture receiver 13 (string galvanometer, oscillograph or the like; voltage receivers such as glow light tubes and Kerr cells could also be suitably controlled by the changes effected by the thermionic valve 9), in which the presence of the synchronizing current impulses need not be considered 20 so far as regards the reception of the picture. For obtaining this latter purpose, the string galvanometer could be set for instance in such a manner that for the frequency signs it is deflected merely to an extent at which 25 a production of picture does not take place. Only signals, the intensity of which is greater than that of the frequency signs, produce an effective deflection of the galvanometer. Obviously, however, the reverse might be the 30 case, i. e., the synchronizing signs may be of greater intensity than the picture signs and the galvanometer may be so adjusted that it will not be deflected by the synchronizing signs alone but only when the current is of 35 a certain amplitude, that is, when the picture signs are present with the synchronizing signs.

In order to utilize the frequency signs for the regulation of a synchronous motor—the 40 path to the same is indicated by 18—separately from the picture signs, the anode current of the valve 9 is amplified once more by sending the current from the positive end of the battery 12 through a resistance 14 and 45 by applying the potential behind the said resistance to the grid 15' of the valve 15; the cathode 16 receives its potential from a suitable intermediate point of the battery 12; a still further amplified anode current from 50 the cathode 16 to the anode 17 is obtained from the anode battery 19. This amplified current, which is to be used for the regulation of the synchronous motor in the receiver should already have such an intensity that 55 in the case of the frequency signs saturation is reached, whilst the picture signs in the same should no longer be noticeable. In place of the telautographic transmitter there could also be used a transmitter operated by 60 65 the photoelectric cell system, in which the

picture signs are not merely "yes" and "no" signs, but signs which are graded to suit the picture elements and which are superimposed on the frequency signs, so that the signs assume the shape shown in Figure 4. The arrangements in the receiving apparatus remain the same. In the case of black and white pictures, even when photo-electric cells are used the signs reaching the receiver will again have the shape shown in Figure 8.

When it is a question of transmission through wires, and when the arrangement with the interrupter disc 4 is used in the transmitter, it will no longer be so easy to separate the frequency signs from the picture signs in the receiver on account of the flattening of the signs by the capacity influence. For this purpose there is then used the arrangement according to Figure 6.

In this last mentioned arrangement 20 is an alternating current generator, the frequency of which is determined by the capacity of the line. The alternating currents go through the inductance 21, arranged in parallel to the telautographic transmitter 1, 2, through the plug contact 7 into the line. As long as the feeler pin 2 does not make contact, periodic signs of the form shown in Figure 7 will be produced. As soon however as the pin 2 makes contact, the signs corresponding to the picture will be superimposed, since the inductance 21 is then cut out, on the frequency signs, for instance in the manner indicated in Figure 8.

The arrangement in the receiving apparatus remains as shown in Figure 2, only the signs coming through the plug contact 8 will not come from the audion (detector) of a wireless transmitter, but direct from the line. In place of the telautographic transmitter, there can also be used in this case a transmitter worked by the photo-electric cell system; the signs coming from the transmitter could then instead of being of the shape shown in Figure 8, also be for instance of the shape shown in Figure 9. The receiver arrangement in this latter case would again remain the same.

What I claim to be secured by Letters Patent is:

1. In a picture transmitting system, a first station, a second station, means at the first station for generating synchronizing impulses of amplitudes having upper and lower predetermined limits, means for generating picture impulses of varying amplitudes having upper and lower predetermined limits, said amplitude limits of said picture transmitting impulses being outside of the range of said synchronizing impulses and means at the second station for separating said picture and said synchronizing impulses.

2. In a picture transmitting system, a first station, a second station, means at the first station for generating synchronizing currents

of amplitudes having upper and lower predetermined limits, means for generating picture currents of varying amplitudes having upper and lower predetermined limits, said amplitude limits of said picture transmitting currents being outside of the range of said synchronizing currents and amplitude responsive means at the second station for separating said picture and said synchronizing currents.

3. In a signalling system, a first station, a second station, means for generating synchronizing impulses at said first station having upper and lower amplitude limits of a predetermined value, means for generating signalling impulses, having upper and lower amplitude limits, said amplitude limits of said signalling impulses being outside the range of limits of said synchronizing impulses and means at the second station for separating said signalling and said synchronizing impulses.

4. In a signalling system, a first station, a second station, signalling apparatus at said stations, means for generating synchronizing impulses at said first station, having upper and lower amplitude limits of predetermined value, means for generating signalling current having upper and lower limits of predetermined value, the lowest amplitude limit of said signalling current being as great as the highest amplitude limit of the synchronizing currents, means whereby said synchronizing currents maintain the signalling apparatus in synchronism, means whereby said signalling apparatus operate in response to said signalling currents and amplitude distinguishing means at said second station for separating said signalling and synchronizing impulses.

5. In combination with an electric signalling system having synchronously operating transmitting and receiving elements, means for transmitting simultaneously signalling currents and synchronizing current impulses on a common transmission channel, comprising means to produce periodic synchronizing current impulses, further means associated therewith to produce signalling current signals having a zero level equal to the top level of said synchronizing currents, a receiving device for said signalling currents adapted to become operative only with a biasing current at least equal to the strength of said synchronizing currents, and a current limiting device to serve as a segregating means for said synchronizing currents having its limiting value adjusted to be equal to the strength of said synchronizing currents.

6. In combination with an electric signalling system having synchronously operating transmitting and receiving elements, means for simultaneously transmitting signalling currents and synchronizing current impulses

over a common circuit comprising means to produce periodic synchronizing current impulses, further means associated with said first means to produce signalling current signals having a zero level equal to the top level of said synchronizing currents, a galvanometer receiving device for said signalling currents so adjusted as to register receiving currents of greater than maximum intensity of said synchronizing impulses only and a discharge device having cathode and anode electrodes to produce discharge currents therebetween, control means for said discharge current, a common receiving circuit including said galvanometer device and coupled with said control means, said control means being adjusted so as to effect saturation of said discharge current with a current flowing in said receiving circuit not greater than the maximum strength of said synchronizing currents.

7. In combination with an electric picture transmission system, having synchronously operating transmitting and receiving elements, means for transmitting simultaneously synchronizing current impulses and picture current signals on a common transmission channel comprising means to produce periodic synchronizing current impulses, further means associated with said first means to produce picture current signals in accordance with the scanning elements of a picture to be transmitted and having a zero level above the top level of said synchronizing currents, a receiving device for said picture current adapted to become operative with a biasing current at least equal to the strength of said synchronizing currents, and a current limiting device to serve as a segregating means for said synchronizing currents having its limiting current adjusted to be equal to the strength of said synchronizing currents.

8. In combination with an electric picture transmission system, having synchronously operating transmitting and receiving elements, means for transmitting simultaneously synchronizing current impulses and picture current signals on a common transmission channel, comprising means to produce periodic synchronizing current impulses, further means associated with said first means to produce picture current signals in accordance with the scanning elements of a picture to be transmitted and having a zero level equal to the top level of said synchronizing currents, a galvanometer picture-receiving device adjusted so as to register currents of greater than maximum intensity of said synchronizing currents, and a discharge device having cathode and anode electrodes to produce the discharge current thereby, control means for said discharge current, a common receiving circuit including said galvanometer device and coupled to said control

- means, said control means being adjusted to effect saturation of said discharge current with a current flowing in said receiving circuit equal to the strength of said synchronizing currents.
9. In combination with an electric picture transmission system having synchronously operating transmitting and receiving elements, means for producing, transmitting simultaneously on a common channel, and segregating from each other picture current signals and synchronizing current impulses, comprising a transmitting circuit including in series a current source and a picture scanning device, means to interrupt said circuit periodically during short intervals synchronously with the speed of said scanning device to produce synchronizing current impulses with the picture signals placed on the top level thereof, a common receiving circuit for both said synchronizing currents and picture currents, a light valve in said receiving circuit having its shutter so adjusted as to obstruct the passage of light on currents smaller than said synchronizing currents, and a three electrode vacuum tube for segregating said synchronizing currents having its grid circuit coupled to said receiving circuit and adjusted in such a manner as to become saturated at a receiving current not greater than said synchronizing currents.
10. In combination with an electric picture transmission system, having synchronously operating transmitting and receiving elements, means for producing, transmitting simultaneously on a common channel and segregating from each other picture current signals and synchronizing current impulses, comprising a transmitting circuit including in a series a current source, a picture scanning device, a circuit interrupting device operated synchronously with the scanning speed of said scanning device, whereby periodic synchronizing current impulses with small spacing intervals are produced having the picture current signals placed on the top level thereof, a common receiving circuit for said picture currents and synchronizing currents, a light valve in said receiving circuit arranged and adjusted as to obstruct the passage of light for currents smaller than the top level intensity of said synchronizing impulses, a three electrode vacuum tube for segregating said synchronizing currents having main electrode and a control electrode, a biasing battery in series with a coupling resistance connected to said control electrode and also coupled with said receiving circuit and so adjusted as to effect saturation of the output current of said vacuum tube with current in said receiving circuit not greater than said synchronizing currents.
11. In combination with a picture transmission system, means for simultaneously transmitting synchronizing current impulses and picture signal currents, comprising means for producing periodic synchronizing current impulses having small spacing intervals, further means associated with said first means to produce picture current signals having as a zero amplitude level the top amplitude level of said synchronizing impulses and means for separating both currents consisting respectively of a device acquiring a bias at least equal to the top value of said synchronizing currents and a current limiting device having a limit value not greater than the intensity of said synchronizing impulses.
12. In a picture transmission system using synchronously operating transmitting and receiving elements, the method of transmitting simultaneously on a common channel and separating from each other, synchronizing current impulses and picture signal currents which consists in placing the picture signals on a different amplitude level equal thereon the synchronizing current impulses and separating both currents, by using the synchronizing currents as operating biasing current and as limiting current for the picture current receiver and the synchronizing current receiver respectively.
13. In a picture transmission system using synchronously operating transmitting and receiving elements, the method of transmitting simultaneously on a common channel and separating from each other, synchronizing current impulses and picture signal currents which consists in placing the picture signals on a different amplitude level equal thereon the synchronizing current impulses and separating both currents.
14. A picture transmission system having synchronously operating scanning devices and picture reproducing apparatus, means to transmit unilateral picture current impulses varying in accordance with picture characteristics of elementary portions of the picture to be transmitted, further means for transmitting unilateral periodic synchronizing current impulses characteristic of the scanning speed of said picture, both series of impulses being superimposed upon each other for transmission over a common electric channel, and means at the receiving end for separating said impulses from each other, said last means comprising marginal current responsive devices adjusted in respect to the intensity values of said picture current impulses and said synchronizing current impulses respectively.
15. In a picture transmission system having a picture transmitting station and a picture receiving station remotely disposed from each other, an image at said transmitting station, means for translating elementary portions of said image into variable direct currents in accordance with variations of the image characteristics, further means

simultaneously operative with said translating means for transmitting direct current periodic synchronizing currents in accordance with the speed of operation of the translating means in covering successive portions of the picture, the picture and synchronizing currents being superimposed upon each other and upon a common electric channel and current responsive means at the receiving station for separating said picture and synchronizing currents from each other.
